UNITED STATES PATENT OFFICE

138,566

DESIGN FOR A TOY REVOLVER

Carl F. Bollmeier, Milwaukee, Wis.

Application May 4, 1944, Serial No. 113,474

Term of patent 3½ years

(Cl. D34—15)

To all whom it may concern:

Be it known that I, Carl F. Bollmeier, a citizen of the United States, residing at Milwaukee, in the county of Milwaukee and State of Wisconsin, have invented a new, original, and ornamental Design for a Toy Revolver, of which the following is a specification, reference being had to the accompanying drawing, forming part thereof.

taken from the rear and one side and illustrating my new design; and

Figure 2 is a perspective view thereof taken from the front and opposite side.

I claim:

The ornamental design for a toy revolver, as shown.

CARL F. BOLLMEIER.
